UNITED STATES PATENT OFFICE.

CHARLES F. BURROUGHS, OF EAST ORANGE, NEW JERSEY, ASSIGNOR TO COMPOSITION MACHINERY CORPORATION, OF NEWARK, NEW JERSEY, A CORPORATION OF NEW JERSEY.

PRESS FOR MOUNTING SOUND-MATRICES.

1,328,264.

Specification of Letters Patent. Patented Jan. 20, 1920.

Application filed June 15, 1918, Serial No. 240,188. Renewed October 3, 1919. Serial No. 328,332.

To all whom it may concern:

Be it known that I, CHARLES F. BURROUGHS, a citizen of the United States, residing at 122 Prospect street, East Orange, 5 county of Essex, State of New Jersey, have invented certain new and useful Improvements in Presses for Mounting Sound-Matrices, fully described and represented in the following specification and the accompanying 10 drawings, forming a part of the same.

This invention consists of a special form of hydraulic press which is adapted to perform various pressing operations, but is designed particularly to press a thin flexible 15 metallic matrix upon a rigid bed-piece while the two are secured firmly together at the margin.

In the manufacture of phonographic disk-records, the matrix consists of such a thin 20 disk of metal, which must be firmly connected to a bed-piece, by which it may be held in the molding-press and heated and cooled in accordance with the requirements of the molding operation.

25 Heretofore, such thin matrices have been secured at their margin to a flat metallic bed-piece adapted to readily transmit changes of temperature to the matrix when used in a molding-press.

30 The present invention furnishes means for pressing the thin matrix very strongly upon the surface of its bed-piece while the margin of the matrix is secured thereto.

It has been found that the mere attachment 35 of the matrix at its edge to the base-piece is not sufficient to hold the matrix in a completely flattened condition, as the process of manufacturing the matrix does not impart to it a perfectly plane surface to contact with the bed-piece.

The present invention furnishes means, without injuring the matrix, to press it very 40 strongly toward the bed-piece and to thus hold it while the margin of the matrix is secured thereto. This treatment of the matrix while fastening it to the bed-piece, is found to flatten the matrix perfectly and produce a uniform contact between the matrix and the bed-piece, and to permit the edge of the 45 matrix to be clamped more firmly to the bed-piece. This results in the flattening out

of any inequalities in the form of the matrix, and thus slightly spreading its margin which, when firmly secured to the bed-piece, continues to hold the matrix in a flattened 55 condition.

The invention will be understood by reference to the annexed drawing, in which Figure 1 is an elevation of a hydraulic press adapted for use in the mounting of the matrices upon their bed-pieces; Fig. 2 is a transverse section on line 2—2 in Fig. 1, upon a larger scale than that figure; Fig. 3 is an elevation of the "force", removed from the upper part of the hydraulic press and drawn, partly in central section, upon the same scale as Fig. 2; Fig. 4 is a plan of the "force" upon the same scale as Fig. 3; Fig. 5 shows a bed-piece and matrix in section upon a much larger scale, with portions of 70 the "force" and "head" employed to press the parts together, the lower portion of the head and the attached ram not being in section; Fig. 5^a is an enlarged section of the clamping-ring and its connected parts; Fig. 75 6 is an edge view of the clamping-ring for the matrix; Fig. 7 is a plan of the parts below the top of the bed-piece in Fig. 5; and Fig. 8 is a plan of the head with the spring-plate therein. 80

The chief operative parts of the invention are shown in Fig. 5, where *a* designates a "head" movable toward and from a "force" or platen *C*, between which "head" and "force" the bed-piece *c* and matrix *d* are 85 clamped, while a clamping-ring *e* is pressed upon the edge of the matrix by screw-studs *f* extended through holes in the bed-piece and locked therein by nuts *g*.

Sockets *h* are formed in the bed-piece to 90 receive the nuts, so that their outer sides are nearly flush with the outside of the bed-piece. The sockets afford room for the application of a wrench. The head of such a wrench, and part of the handle, is shown in 95 section in Fig. 5.

The clamping-ring is formed with a shoulder *e'* embracing the periphery of the matrix *d* and with a jaw forming an annular ridge *e²* over the margin of the matrix. 100

A hole *i* is formed through the center of the matrix and bed-piece, and a flanged pin

j is shown screwed into said hole with its flange *k* clamping the middle portion of the matrix firmly upon the bed-piece.

The head *a* is provided with an annular groove *l* to receive the ridge *e*² upon the clamping-ring, and the head is formed, inside the line of such groove, with a recess *m* in which an annular spring-plate *n* is fitted movably around a hub *n'* in the center of such recess. The hub is formed with a hole *o* to receive the projecting end *o'* of the pin *j*, which centers the parts upon the head.

A series of springs *p* is located in the recess under the spring-plate, tending to force the same normally upward, and such movement is limited by screws *p'*, the heads of which are fitted to sockets *p*² in the spring-plate. The spring-plate is faced with a layer *m'* of elastic material, as felt, which contacts with the operative side of the matrix *d* during the pressing operation.

The means of pressing the head and force together is shown in Figs. 1 and 2, in which a suitable four-sided frame *A* is shown provided in the bottom with a hydraulic cylinder *B*, and in the upper part with a force or platen *C*.

The head *D* is provided with a ram *D'* fitted to the cylinder *B*, and guides *E* are shown upon the frame to keep the head *D* from turning. The force *C* is secured in the top of the press by a shank *C'* and nut *C*².

The frame *A* is provided with a downwardly projecting pedestal *A'* which is supported upon a stand *F* having a socket *G* in the center provided with a hydraulic supply by pipe *H*. To operate the press, said pipe requires connection to a hydraulic accumulator, and also to a waste-pipe.

40 The pedestal is shown with a flange *I* to rest upon the top of the socket *G* and with a boss *J* upon its lower end fitted to rotate in the socket for the purpose herein described. The boss is made smaller than the socket to admit hydraulic packings *K* which embrace the boss in the upper and lower ends of the socket and prevent any leakage therefrom. The boss is adjusted to turn in the socket by means of a washer *L* and nut *L'* fitted to a threaded stud *M* in the bottom of the socket.

45 The center passage *A*² in the pedestal connects the cylinder *B* with the boss *J*, and holes *r* through the sides of the boss permit the fluid under pressure to enter the boss and operate upon the ram *D'*. An anti-friction washer *I'* is inserted between the flange *I* and the top of the socket.

50 A rotatable construction for the pedestal upon the stand *F* is preferable, to enable the operator without changing his position to tighten successively the nuts *g* which are provided to secure the clamping-ring and matrix tightly upon the bed-piece.

The operation of securing the matrix upon a bed-piece is as follows:

The hole *o* in the central hub serves to center the bed-piece and matrix upon the head, and the groove *l* serves to receive the annular jaw upon the clamping-ring and to support it under the pressure to which it is subjected. The spring-plate *n* is adjusted to contact with the surface of the matrix before the clamping-ring is fully seated in the groove *l*; so that when fully seated the spring-plate presses the matrix forcibly toward the bed-plate. Such seating of the jaw *e*² in the groove *l* is only effected when the head *D* is forced upwardly by the hydraulic ram at the pleasure of the operator, thus pressing the head forcibly toward the force *C*, which crowds the bed-piece downward with the spring-plate *n* until the jaw *e*² of the clamping-ring is fully seated in the groove *l*, and thereafter holds the parts pressed together with great force while the clamping-ring is tightened upon the edge of the matrix. In this seating movement of the bed-piece, it is guided by the central pin *o'*.

90 The pressure of the spring-plate against the matrix flattens the latter out perfectly when the clamping-ring is wholly seated, and the final effect of the pressure is to crowd the jaw of the clamping-ring firmly upon the edge of the matrix, as shown in Figs. 5 and 5^a, so that the matrix is gripped to the bed-piece more firmly than could be effected by any agency short of a hydraulic pressure. While in this closely pressed state, the clamping-ring is tightly secured by applying a wrench *t* to the nuts upon the studs *f* of the clamping-ring.

95 The studs *f* are formed upon the clamping-ring close to the jaw of the latter, so that the nuts upon the set-screws may hold the jaw firmly, and the force *C* could not press the jaw firmly against the edge of the matrix without partially covering the said nuts, except the edge of the jaw were notched to clear the nut. The hydraulic pressure is, however, concentrated upon the clamping-ring by forming the force, as shown in Figs. 3 and 4, with notches *b* in its edges corresponding in number to the screws *f* and nuts *g*.

100 By this construction the fingers upon the force, intermediate to the notches, may extend out to the extreme edge of the bed-piece and exert the full pressure upon the clamping-ring, while the notches expose the nuts to access while the ring is thus clamped for applying the wrench *t* which is shown partly in section at the left side of Fig. 5.

105 With the clamping-ring pressed to the bed-piece by the hydraulic pressure, the wrench is enabled to screw the nuts down more tightly and thus enable them to re-

tain the clamping-ring in the position to which it has been crowded by the action of the force.

By partly rotating the press upon its stand after tightening each nut *g*, the operator can bring all the nuts successively to his hand without changing his position.

Having thus set forth the nature of the invention what is claimed herein is:

- 10 1. The means for mounting a thin matrix upon a bed-piece having a clamping-ring upon its margin to engage the edge of the matrix such means consisting of a head and force movable in relation to one another with means for pressing them forcibly together and the head provided with an annular seat to receive the clamping-ring, and the force being fitted to press upon the bed-piece opposite to the said ring.
- 20 2. The means for mounting a thin matrix upon a bed-piece having a flanged pin in the center and a clamping-ring upon its margin adapted respectively to engage the center of the matrix and the edge thereof, such means consisting of a head and force movable in relation to one another with means for pressing them forcibly together and the head provided with an annular seat to receive the clamping-ring, and the force being fitted to press upon the bed-piece opposite to the said ring.
- 30 3. The means for mounting a thin matrix upon a bed-piece having a clamping-ring upon its margin with screws and flanged nuts for securing it to the bed-piece, consisting of a seat for the matrix and bed-piece and a force for pressing them upon the seat, the said force having notches in the edge to clear the flanged nuts to permit the tightening of said nuts while the bed and matrix are under pressure.

- 40 4. The means for mounting a thin matrix upon a bed-piece having a clamping-ring upon its margin with a ridge over the clamping-jaw of said ring, and screws and flanged nuts for securing the clamping-ring to the bed-piece, which means consists of a head having an annular seat to receive the ridge of the clamping-ring, and a force extended to the margin of the clamping-ring and having notches upon its edges adjacent to the nut to permit the turning of the same.

- 50 5. The means for mounting a thin matrix upon a bed-piece having a clamping-ring upon its margin with a ridge over the clamping-jaw of said ring, and screws and flanged nuts for securing the clamping-ring to the bed-piece, which means consists of a head having an annular seat to receive the ridge of the clamping-ring, a spring-plate within the annular seat to press the surface of the matrix against the bed-piece, a force applied to the outer side of the bed-piece, and means for moving the seat and force

relatively to one another to press the edge 65 of the matrix firmly upon the bed-piece while securing the clamping ring in its final adjustment.

6. The means for mounting a thin matrix upon a bed-piece having a clamping-ring 70 upon its margin with a ridge over the clamping-jaw of said ring, and fastening-means for securing said ring to the bed-piece, which means consists of a movable ram with head having upon the top an annular seat with groove to receive the ridge of the clamping-ring, the head having a recess within such annular seat, a disk fitted movably within the said recess with springs forcing the same normally outward to form 80 a spring-plate for the matrix, and a force covering the bed-piece and having notches in the edge, whereby the fastenings of the ring may be adjusted while the bed and matrix are under pressure.

85 7. The means for mounting a thin matrix upon a bed-piece having a flanged screw-pin in the center to clamp the center of the matrix thereto and having a clamping-ring upon the margin with a ridge over the 90 clamping-jaw of said ring and screws for securing the ring to the bed-piece, such means consisting of a movable ram with a head having upon the top an annular seat with groove to receive the ridge of the 95 clamping-ring, the head having a recess within the annular seat, a hub in the center of the same with socket to receive the center pin, an annular spring-plate fitted movably between the hub and the annular grooved seat 100 with a yielding facing upon its outer side, springs fitted beneath the spring-plate to press it normally outward, means to limit such outward movement, and a force operating to press the bed-piece, the matrix and 105 the clamping-ring firmly together, while the clamping-ring is secured to the bed-piece.

110 8. A mounting press for clamping a circular matrix upon a bed-piece by a clamping-ring, consisting of a suitable frame, a suitable force fixed in one end of the frame, a head movable in the opposite end of the frame and provided with an annular seat to receive the clamping-ring, and means for 115 pressing the head toward the force.

120 9. A mounting press for clamping a circular matrix upon a bed-piece by a clamping ring having an annular ridge, consisting of a rectangular frame having a force in its upper part with notches upon its edge, a head movable in its lower part and provided with an annular grooved seat to receive the ridge upon the clamping-ring, and means for pressing the head upwardly to- 125 ward the force.

10. A mounting press, consisting of a suitable frame with a hydraulic cylinder in its

- lower end, a head movable in the frame with ram fitted to the cylinder, a force secured in the upper part of the frame, a suitable stand with socket having a hydraulic connection, 5 a pedestal extended downward from the frame and fitted rotatably to the socket, and connection from the socket through the pedestal to the cylinder to supply the hydraulic fluid thereto.
- 10 11. A mounting press for clamping a circular matrix upon a bed-piece by a clamping-ring, consisting of a suitable frame with a hydraulic cylinder in its lower end, a head movable in the frame with ram fitted to the cylinder, a force secured in the upper part of the frame, a suitable stand with socket having a hydraulic connection, a pedestal 15 extended downward from the frame and having flange to rest upon the stand, and a boss extended within the socket and having annular packings between the said boss and socket at the upper and lower ends, the base 20 having holes extended through its sides, and a center passage extending from the holes through the pedestal to the cylinder, and means for securing the boss rotatably in the socket of the stand.
12. A mounting press for clamping a circular matrix upon a bed-piece by a clamping ring, consisting of a suitable frame with a 25 hydraulic cylinder in its lower end, a head movable in the frame with ram fitted to the cylinder, a force secured in the upper part of the frame, a suitable stand with socket having a hydraulic connection, a pedestal 30 extended downward from the frame and having flange to rest upon the stand, and a boss extended within the socket and having annular packings between the said boss and socket at the upper and lower ends, the base 35 having holes extended through its sides, and a center passage extending from the holes through the pedestal to the cylinder, and means for securing the boss rotatably in the socket of the stand. 40

In testimony whereof I have hereunto set my hand.

CHARLES F. BURROUGHS.
